UNITED STATES PATENT OFFICE

SIDNEY I. PICKER, OF NEW YORK, N. Y.

DESIGN FOR A TRAY

Application filed May 19, 1932. Serial No. 43,845. Term of patent 7 years.

To all whom it may concern:

Be it known that I, SIDNEY I. PICKER, a citizen of the United States, residing at 180 East 79th Street, New York city, in the county of New York and State of New York, have invented a new, original, and ornamental Design for a Tray, of which the following is a specification, reference being had to the accompanying drawing, forming part thereof.

Fig. 1 is a plan view of a tray showing my new design.

Fig. 2 is a side elevation of the same.

The three large circular recesses may be used for holding drinking glasses or ash trays. I particularly contemplate two of such recesses being used to hold drinking glasses and the third being used to hold an ash tray. The rectangular recess is intended to hold a book of matches, and the small circular hole adjacent to it is intended to receive a pencil or a lamp standard.

I claim:

The ornamental design for a tray substantially as shown and described.

SIDNEY I. PICKER.
